UNITED STATES PATENT OFFICE.

OSCAR RICHTER AND ERIK L. VOGNILD, OF CHICAGO, ILLINOIS.

ENVELOP.

SPECIFICATION forming part of Letters Patent No. 658,926, dated October 2, 1900.

Application filed March 29, 1899. Serial No. 710,948. (No model.)

To all whom it may concern:

Be it known that we, OSCAR RICHTER and ERIK L. VOGNILD, citizens of the United States, residing at Chicago, in the county of 5 Cook and State of Illinois, have invented a new and useful Improvement in Envelops, of which the following is a specification.

Our invention relates particularly to an improvement in envelops or covers for use in 10 sending money or valuables from one place to another or in forwarding important secret despatches or the like.

Our object is to provide means for preventing tampering with envelops of this character, as for the purpose of theft or of gaining 15 knowledge of the despatch being forwarded.

We accomplish our purpose, preferably, by supplying the blank from which the envelop is made with comparatively-stiff wires secured 20 thereto or embedded therein in such manner that after the envelop is formed the wires are so located as to act as a safeguard against the envelop being cut, and in addition to this precaution improved means are supplied for preventing 25 the unsealing of the envelop.

In the accompanying drawings, Figure 1 is an inner view of an envelop-blank constructed in accordance with our invention; Fig. 2, a view of the reverse side of the sealed envelop; Fig. 3, an enlarged broken sectional view on line 3 of Fig. 1, and Fig. 4 a view of 30 a transparent piece of paper or the like to be applied to the envelop as a safeguard against unsealing.

35 A represents an envelop, shown in reverse side. The envelop is formed from a blank A', supplied in the process of manufacture or subsequently with comparatively-stiff wires a b, crossing each other, as shown. The wire 40 ribs are preferably so located as to cross each other at right angles, so as to render it impossible to cut along any edge of the envelop or parallel to any edge on either side for any considerable distance without encountering a 45 rib. If a rib be cut, it is not possible to so reseal the envelop as to prevent detection. The wires are shown held in place by strips 50 of paper or cloth a' b', cemented to the inner surface of the blank. As stated, however, they may be located in the paper or material of the blank during the manufacture thereof. The number of wires may be increased at will.

If the ribs be cut in an effort to make a sufficiently-large incision to extract the contents of the envelop, the fact is readily exposed by 55 bending the envelop, and thereby causing the ends of the ribs to protrude. The wires may be replaced by ribs of any material suited to the purpose the severed ends of which could be caused to tear the paper and protrude by 60 bending the envelop. In other words, the value of this feature of the improvement lies not alone in the increased difficulty of making a sufficiently-large incision to permit the envelop contents to be abstracted, but also in 65 the impossibility of concealing the cut effectively by resealing. Ribs of any material which will render them difficult of confinement may be used, therefore, so long as they are of a nature not to interfere with the proper 70 forming of the envelop. Spring-metal wire possesses this absolutely-necessary quality in a high degree, and its use is therefore preferred.

Figs. 2 and 4 show the improved means for 75 preventing unsealing of the envelop. This feature of the improvement, while not limited in its application to use in connection with the improved form of envelop here shown, is in the present application claimed only in combination with said improved envelop.

Fig. 2 shows the envelop provided on the reverse side, at and about the lines of sealing, with characters comprising the address and indicating the amount contained in the 85 envelop. These characters are preferably formed with an indelible pencil and when applied are dry and inconspicuous. When moistened, as by the use of steam in an effort to unseal the envelop, the ink changes color 90 and spreads, the characters becoming very prominent, and the ink being caused to penetrate the material of the envelop in a manner to prevent its removal. The characters are shown written within a space c, (indicated by 95 dotted lines,) to which space is applied a transparent strip of material c'. The strip c is preferably of thin paper of a comparatively-porous nature and may be supplied with one gummed surface to permit its ready application to the 100 surface to be protected. The ink characters may be applied to the envelop and then covered by the transparent material, or the transparent strip may be gummed to the envelop

after the latter is sealed and the characters then written. If the latter method is pursued, it is quite important that the transparent protecting-strip be sufficiently porous 5 to act as a transfer-sheet when moisture is applied in order that the envelop shall receive the ink therefrom when the latter is moistened. Obviously it is impossible to apply a knife beneath the protecting-strip without 10 the effects being noticeable through the transparency, and it is impossible (for the reasons stated) to remove the protecting-strip intact to enable the knife to be inserted.

As plainly appears from Fig. 2, the space 15 which is occupied by the transparent strip c' is comparatively large, leaving only short lines of sealing of the envelop exposed. The importance of this feature is evident when it is remembered that the lines of sealing afford 20 practically the only necessarily-difficult places to provide against cutting. The use of long black lines on an envelop would afford another danger; but this use may be avoided. The lines of sealing, however, are 25 necessarily present, and the transparent strip c' should be of sufficient size to prevent a line of sealing from being exposed continuously far enough to permit an incision of such size as to allow the extraction of the envelop 30 contents. The writing of the address across the lines of sealing serves the important purpose of directing the eyes of the clerk to the transparent seal c' and to that portion of the envelop where any attempt to open the envelop 35 would most likely be made. The use of an indelible pencil or the like for forming the characters prevents the use of steam or moisture. The use of the transparency prevents the use of a knife. Both act together to 40 protect the lines of sealing of the envelop, and it would seem that the use of one without the other or some equivalent thereof would defeat the object wholly or in part. The same may be affirmed of the use of either 45 the wires or the transparent seal without the use of both.

The side of the envelop not shown is to contain the necessary instructions to agents or employees and such other matter as may 50 be necessary or convenient.

Efforts have heretofore been made to protect currency contained within an envelop by sewing through the envelop and the contained bills and passing the cord about the 55 envelop and fixing with sealing-wax. Such a construction is insecure, however, for the rea-

son that both cord and envelop may be cut beneath the sealing-wax and on lines where the effect is not noticeable and the envelop resealed in a manner to escape detection. 60 With our improved construction no lines are afforded where an incision can be made without detection.

We do not limit ourselves to the exact material shown and described nor to any particular method of manufacture for the envelop-blank or method of procedure in applying ink characters and transparent protecting material. For the purpose of the claims the space on the envelop beneath the transparent piece is to be regarded as the surface to be protected, even though the ink characters are applied to the outer surface of said transparent piece.

What we claim as new, and desire to secure 75 by Letters Patent, is—

1. In an envelop, the combination with the envelop-body, of stiff metallic wire ribs attached to the material of the body and crossing each other, substantially as and for the 80 purpose set forth.

2. In an envelop, the combination with the body thereof of comparatively-stiff ribs of wire or the like, a transparent protecting-piece applied to the envelop at a line of sealing, and characters of indelible ink or its equivalent in close juxtaposition to said transparent piece, substantially as and for the purpose set forth. 85

3. In an envelop, the combination with the body thereof of ribs of wire or the like, characters of indelible ink or the like applied to the envelop at the line of sealing, and a comparatively-large piece of transparent paper or the like above the characters and crossing 95 the lines of sealing and cemented in place, substantially as and for the purpose set forth.

4. In an envelop, the combination with the envelop-body, of stiff longitudinal and transverse ribs attached to the material of the body 100 and crossing each other, said ribs extending across one side of the envelop and about the lateral and end edges thereof and back on the reverse side to protect the same, and a seal covering the ends of both longitudinal and transverse ribs, substantially as and for the purpose set forth. 105

OSCAR RICHTER.
ERIK L. VOGNILD.
